(Cl. D14—3)

Fig. 3

FIG. 1 is a front perspective view of a display truck showing our new design.

FIG. 2 is a side elevational view thereof.

FIG. 3 is a rear perspective view thereof, taken from the same side as shown in FIGS. 1 and 2.

The side opposite to that shown is the same as the side shown in FIGS. 1, 2, and 3 and the essential features of our design reside in those portions shown in solid lines.

We claim:

The ornamental design for a display truck, substantially as shown and described.
